SHARP FREEZING CONTAINER

Filed Feb. 1, 1929

UNITED STATES PATENT OFFICE

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN

SHARP FREEZING CONTAINER

Application filed February 1, 1929. Serial No. 336,889.

This invention relates to sharp freezing containers, and has to do particularly with that type of sharp freezing container formed of rubber or other material to which ice does not readily adhere.

Heretofore, as fully set forth in my Patent No. 1,675,599, sharp freezing containers or rubber trays for domestic refrigerators have been formed of rubber or other flexible material, and some of these trays have been formed entirely of rubber of sufficient rigidity to stand up, and others have been formed of very thin rubber or separate individual rubber containers reinforced by suitable metal containers. Such sharp freezing containers have proven very satisfactory in most all types of domestic refrigerators, but in a few refrigerators difficulty has been experienced in effecting freezing of the ice cubes.

A great many details enter into this transfer of heat to freeze the ice cubes, but the fact remains that in some types of refrigerators the freezing period is unduly prolonged.

It is the object of the present invention to provide a sharp freezing unit which will greatly facilitate the freezing of the ice cubes and thus greatly decrease the time of freezing of a tray of water. This novel result is accomplished by combining a flexible or rubber tray with a standard metal sharp freezing tray. More specifically, the present invention contemplates the provision of a sharp freezing container formed into a plurality of compartments for defining the ice cubes, the greater portion of the surface area of such compartments being formed of rubber or other material to which ice does not readily adhere, and the remaining surface area of each compartment being formed of metal or other high heat conducting material.

By the provision of such container, it will be obvious that the walls of each ice cube compartment will be such as to effect comparatively easy removal of the ice cubes, but a portion of the wall will be such as to readily conduct heat units so as to materially increase the rapidity of freezing of the ice cubes. While the removal of the ice cubes will not be as easy or perhaps as quick as where the entire unit is formed of rubber, or

similar material, yet the flexibility of the walls will permit such easy removal of the ice cubes that the time gained in freezing will offset any difficulty that might be encountered in removing the ice cubes.

55

In the drawings:

Fig. 1 is a perspective view of the flexible sharp freezing container provided with metallic inserts in the base of each ice cube compartment.

60

Fig. 2 is a plan view of the structure shown in Fig. 1 and illustrating different forms of metal discs that may be placed in the bottom of each compartment.

65

Fig. 3 is a perspective view of an individual ice cube compartment provided with a metal heat transmitting means.

Fig. 4 is a sectional view taken through the base of the tray and illustrating a modified manner of inserting the metal disc in the bottom of the compartment.

70

Fig. 5 is a view similar to Fig. 4 but illustrating a further modification of the metal heat transmitting means and manner of inserting the same in the tray.

75

The sharp freezing compartments in various domestic refrigerators vary within wide limits, both as to dimensions and refrigerating capacity. In addition to this variation, there are different requirements as to the size and number of ice cubes to be formed in each sharp freezing compartment. It will therefore be understood that the sharp freezing container, as embodied in the present invention, may be widely varied in design and construction without departing from the invention.

80

Fig. 1 illustrates an embodiment of only one type of sharp freezing container. This container, which is generally designated 1, is preferably formed of rubber which is relatively flexible. In the figure, the walls are shown as being relatively thick whereby the unit may be inherently rigid, but it will be understood that such walls may vary greatly in thickness and that a metal reinforcing container may be utilized to reinforce the rubber trays and maintain the same in operative position.

85

Whatever may be the thickness and ar-

angement of the flexible walls of rubber or other material, I prefer to form the side walls 2 of each ice cube compartment of this material as well as a portion 3 of the bottom 5 walls. In each bottom wall of each compartment I preferably mold an insert 4 of a metal preferably of relatively high heat conductivity. This metal insert 4 may be molded into the lower wall of each compartment, as 10 shown in Fig. 1, or may consist of two parts as shown at 5 and 6 in Fig. 4, and such two parts secured together by means of a suitable screw 7 or other suitable fastening means.

In the modification shown in Fig. 4 it will 15 be understood that the edges of the aperture for receiving the disc 5 and 6 may be molded or they may be squeezed together in the assembling of the disc. The point is that the metal insert 4 in the bottom of each compartment extends through the wall, and in fact forms a part of the bottom wall of each compartment, with the result that rapid transference of heat units is effected between the sharp freezing unit and the water or other 20 liquid within each compartment.

It will be understood that the inserts 4 25 may vary in size and thickness in accordance with the ice cube compartments and in accordance with the design of the particular sharp freezing unit and its refrigerating capacity. If the sharp freezing unit is such as to maintain a relatively low temperature, then of course, the metal insert may be relatively small, or if the sharp freezing 30 unit is provided with a metallic shelf which supports the entire bottom of the tray, then of course, the heat units will be transferred more quickly and a relatively small metal insert would be used in this case. The 35 main point is that the greater part of the surface area of each ice cube compartment is formed of a material to which ice does not readily adhere, and preferably a flexible material such as rubber, while a relatively small portion of the surface area of each compartment is formed of material of relatively high conductivity extending through the wall thereof.

In the modification shown in Fig. 5, instead of the complete insert or disc extending 40 all the way through the bottom wall of the tray, I have shown a disc as being molded in the bottom of the tray and a plurality of small rivets extending upwardly through the remainder of the wall. These small rivets 45 will serve to greatly increase the transference of heat units, and being separated as shown, they will only contact with the ice at spaced 50 points, with the result that the removal of the ice will be somewhat easier than where the entire surface of the disc is exposed. In Fig. 5, I have shown a single individual ice 55 cube container 8, a plurality of which may 60 be inserted in a suitable reinforcing con-

tainer. Otherwise, the construction is the same as shown in the other figures.

In operation, water or other liquid may be poured into the tray and the same, with or without an outside container, inserted in the sharp freezing chamber of the low side. The metal insert will greatly accelerate the transference of heat units whereby even with a low refrigerating capacity, the cubes will be formed within a relatively short time. 70 As the tray 1 is preferably formed of rubber or other flexible material, the entire unit may be given a twist so as to loosen the cubes from the metal inserts or, if desired, to remove only an individual cube. The bottom 80 and side walls of the trays adjacent such cube may be distorted so as to readily eject the same. Inasmuch as the ice cube will not adhere to the greater part of the surface area of each compartment, it will be a relatively 85 easy matter to distort the cube from the disc in the bottom of the compartment, whereas it would be a rather difficult matter to remove the ice cube if one or more of the side walls were formed of metal, in addition to 90 the bottom wall. Even if the side walls of the tray were relatively rigid, it will be obvious that it would be a relatively easy matter to remove the ice cube because it would be only necessary to invert the tray and pour 95 water upon or otherwise heat the metal inserts in the bottom wall of each compartment.

What I claim is:

1. A sharp freezing container of the type 100 adapted to be positioned in heat conducting relation with the cooling unit of a mechanical refrigerating system, comprising walls for defining the shape and size of the article or articles to be frozen, at least a portion of the 105 surface area of said walls being formed of a material to which ice does not readily adhere, and an insert of relatively high heat conducting material in the bottom wall to assist in the transmission of heat for accelerating the 110 freezing of the article or articles.

2. A sharp freezing container of the type 115 adapted to be positioned in heat conducting relation with the cooling unit of a mechanical refrigerating system, comprising walls for defining the shape and size of the article or articles to be frozen, said walls being formed of rubber, and one of the walls being provided with a metal insert for increasing 120 the transmission of heat units for accelerating the freezing of the article or articles.

3. A sharp freezing container of the type 125 adapted to be positioned in heat conducting relation with the cooling unit of a mechanical refrigerating system, comprising walls for defining the shape and size of the article or articles to be frozen, said walls being formed of a flexible elastic material, and one of the walls being provided with a metal insert for increasing 130 the transmission of heat units

for accelerating the freezing of the article or articles.

4. An integral sharp freezing container of the type adapted to be positioned in heat conducting relation with the cooling unit of a mechanical refrigerating system, comprising a series of compartments for forming ice cubes and the like, the walls of said compartments being formed at least in part of a flexible material to which ice does not readily adhere, one of the walls of each compartment being fabricated to effect a relatively greater conductivity than the other walls.

5. A sharp freezing container of the type adapted to be positioned in heat conducting relation with the cooling unit of a mechanical refrigerating system, comprising walls for defining the shape and size of the article or articles to be frozen, the greater portion of the surface area of said walls being formed of a material to which ice does not readily adhere, and an insert of relatively high heat conducting material in one of said walls to assist in the transmission of heat for accelerating the freezing of the article or articles.

25 6. A tray for refrigerating apparatus having integrally formed partitions for dividing the tray into compartments, the greater portion of said walls being formed of a non-metallic flexible material and one of the walls of each compartment being fabricated to effect a relatively greater conductivity than the other walls.

30 7. A container for refrigerating apparatus having an outer wall formed of rubber and partitions formed of rubber for dividing the container into compartments, one of the walls of each compartment being provided with an insert of relatively high heat conducting material.

35 8. A container for refrigerating apparatus, comprising an integrally molded outer wall and partitions for dividing the same into compartments, said walls being formed mainly of a non-metallic flexible material, and the bottom of each compartment being fabricated to effect a relatively greater conductivity than the other walls.

40 In testimony whereof I affix my signature.
50 LLOYD G. COPEMAN.
